APPLY.

UNITED STATES PATENT OFFICE.

EDWARD ERNEST PEMBLE, OF VANCOUVER, BRITISH COLUMBIA, CANADA.

WINDOW-FRAME FOR VEHICLE-CURTAINS.

1,342,460.

Specification of Letters Patent. Patented June 8, 1920.

Application filed January 9, 1919. Serial No. 270,315.

To all whom it may concern:

Be it known that I, EDWARD ERNEST PEMBLE, a subject of the King of Great Britain, and a resident of the city of Vancouver, in the Province of British Columbia, Canada, have invented certain new and useful Improvements in Window-Frames for Vehicle-Curtains, of which the following is a specification.

10 My invention relates to improvements in window frames for vehicle curtains, such as the curtains of automobiles and the like, and the object of my invention is to provide a frame capable of being readily and easily attached to the curtain and so formed that the window is removable with great facility while being firmly held, thus enabling the replacement of a broken window to be effected expeditiously and without defacing or injuring the cover.

I attain this object by the construction illustrated in the accompanying drawings in which—

Figure 1 is a rear view of the window frame and window,

Fig. 2 is a vertical section taken on the line 5—5 of Fig. 1.

Similar figures of reference indicate similar parts throughout the views.

30 The frame consists of two plates 1 and 2 having a window opening formed in each, which opening may be ribbed in any desired fashion, as indicated by the ribs 3 in Fig. 1. One of the plates, that indicated by the numeral 2, is cut longitudinally at a point just above the top edge of the window opening as shown at 4 in Fig. 2, the cut extending the full width of the opening, so that the side and lower edges of the same may be 40 pressed outwardly from the face of the plate, as indicated at 5 in Fig. 2, providing a pocket 10 adapted to receive slidably a celluloid plate 6 which forms the window and which plate is held in place by the 45 edges of the opening in the other plate 1, which edges are pressed out of the plane of the body of the plate so as to be spaced from the edges of the window opening of plate 2 a distance just sufficient to permit 50 insertion of the celluloid window therebetween. To hold the plates together one of them is provided with slots 7 arranged ad-

jacent its outer edges through which may be passed pointed members 9 pressed out of the body of the other plate which members 55 may be bent over after insertion in their respective slots 7.

The manner in which the device is used will be apparent, and to assemble it in place, a suitable opening having first of all been 60 provided in the curtain 9, all that is necessary is to place the plate having the members 8 on the curtain on one side over the opening and press it thereon so that the members 8 pierce the curtain, after which 65 the other plate is placed on the other side so that the members 8 enter the slots 7, these members being then bent over and clenched so that the curtain is firmly gripped between the plates, which then form a permanent window frame adapted to receive 70 slidably in the pocket 10 the celluloid window 6, which, if broken, may be readily withdrawn and replaced by an unbroken one.

75 What I claim as my invention is:

1. A window frame for curtains comprising a pair of plates, projections being pressed out of one of said plates, the other plate being provided with slots adapted to 80 receive said projections, a pocket formed by one of said plates being provided with a longitudinally extending slot and having the sides and lower edges of said plate pressed outwardly, and the edges of the 85 other plate being pressed out of the plane of the body for a purpose specified.

2. A window frame for vehicle curtains comprising a pair of plates each having a window opening and one of which is provided with a plurality of slots, the other being provided with a plurality of integral pointed members adapted to pierce the curtain when pressed thereagainst so as to project through the slots to be bent over on the 90 slotted plate, one of said plates being cut longitudinally above the upper edge of its opening and having the side and lower edges of the same pressed outwardly so as to form with the edges of the opening of the 95 other plate which are correspondingly pressed outwardly a pocket adapted to 100 removably contain a window pane.

EDWARD ERNEST PEMBLE.
